UNITED STATES PATENT OFFICE.

HERBERT E. ENSLIN, OF BEVERLY, MASSACHUSETTS, ASSIGNOR TO UNITED SHOE MACHINERY CORPORATION, OF PATERSON, NEW JERSEY, A CORPORATION OF NEW JERSEY.

BUTTONING MACHINE.

Application filed May 1, 1920. Serial No. 378,107.

To all whom it may concern:

Be it known that I, HERBERT E. ENSLIN, a citizen of the United States, residing at Beverly, in the county of Essex and State of Massachusetts, have invented certain Improvements in Buttoning Machines, of which the following description, in connection with the accompanying drawings, is a specification, like reference characters on the drawings indicating like parts in the several figures.

This invention relates to buttoning machines, and an object of the invention is to provide a machine which will perform buttoning operations with certainty and precision even when the work varies greatly in its characteristics as, for example, when the spacing of the buttons on the button piece and the buttonholes of the buttonhole fly, either on the same or different pieces of work, differs within a wide range or the spacing of the buttons on the button piece fails to accord with that of the buttonholes of the buttonhole fly. The invention aims further to provide a buttoning machine which will operate efficiently on buttons varying within wide limits in size and contour.

With the above and other objects in view, one of the features of the machine, herein shown and described as constituting a preferred embodiment of the invention, resides in novel buttoning mechanism constructed to dispose the material of a buttonhole fly adjacent to one side of a buttonhole of the fly in buttoned relation to a button and then to press the material of the fly at the other side of the buttonhole into buttoned relation to the button, the buttoning mechanism being constructed and arranged to clear the side of the button adjacent to the first-mentioned side of the buttonhole previous to the completion of the buttoning operation and to tip the button over the material of the fly at the first-mentioned side of the buttonhole while the material at the other side of the buttonhole is being pressed into buttoned relation to the button. In the present exemplification of the invention, the buttoning mechanism comprises a buttoning device to which is imparted a substantially straight-line movement to dispose the material of the buttonhole fly adjacent to one side of a buttonhole of the fly in buttoned

relation to a button, and which is then rotated to complete the buttoning operation.

The illustrated machine is designed to perform buttoning operations successively, and important features of the machine consist in a novel organization of parts including devices for effecting relative movement of a button on a button piece and the material adjacent to a buttonhole of a buttonhole fly to cause the button to enter the buttonhole and means for moving the devices to feed the button piece and the buttonhole fly. Preferably, the buttoning devices are moved toward each other in the performance of a buttoning operation and are then moved together while still in engagement with the work following the completion of the buttoning operation and with their work-engaging portions in substantially constant relation to each other to effect the feeding movement of the button piece and the buttonhole fly.

Another feature of the invention resides in a button holder constructed to receive a single button at a time and mechanism co-operating with the holder to perform buttoning operations on the buttons on a button piece with respect to the buttonholes of a buttonhole fly, said mechanism being constructed and arranged to feed the button piece and buttonhole fly past the holder and comprising a buttoning device movable toward a button in the holder. In the illustrated machine, the button holder is in the form of a fork between which and the buttoning device a buttonhole fly may be located so that when the buttoning device is moved toward the button in the fork, it will engage the material of the buttonhole fly adjacent to the corresponding buttonhole of the fly and dispose it in buttoned relation to the button. In order to facilitate the buttoning operation and the subsequent feeding of the button piece and the buttonhole fly, the fork is withdrawn from the button while the buttoning operation is being performed, the button then being upheld by a support constituting a subsidiary buttoning device and co-acting with the main buttoning device to feed the button piece and the buttonhole fly.

The buttoning operation is, preferably, further facilitated by constructing the button supporting fork with two relatively

movable arms and moving one of the arms of the fork away from the other during the performance of each buttoning operation, thus enabling the buttons to be tipped in order to cause them more readily to enter the buttonholes.

Other important features of the invention pertain to a buttonhole finder arranged to ride on the upper surface of the buttonhole fly as it is fed and movable after engagement with a buttonhole of the fly to locate the buttonhole in register with a button in the fork; a button finder for introducing the buttons into the fork; and mechanism for suspending the feeding movement of the work feeding devices when a buttonhole of the fly has been brought into position for location over a button in the holder, such mechanism being preferably, and in the illustrated construction, controlled by the buttonhole finder.

Although the invention is herein described as embodied in a machine for performing buttoning operations successively, it is recognized that many of the features of the invention are capable of use in other relations, for instance, in machines for performing other operations on shoe uppers and in buttoning machines which perform a plurality of buttoning operations simultaneously. Accordingly, it is intended that the scope of the invention shall not be limited except as required by the claims.

Still other objects and features of the invention will be apparent as the description proceeds and will be pointed out in the appended claims.

In the drawings,

Fig. 1 is a view in front elevation of a machine according to the invention;

Fig. 2 is a plan view of the machine;

Fig. 3 is a view in side elevation of the machine, portions of the machine frame being broken away to reveal parts of the interior mechanism of the machine;

Fig. 4 is a detail in plan of the button supporting fork and the finder for moving the buttons into the fork, showing the finder in position to engage about the eye of a button;

Fig. 5 is a view in plan illustrating the fork and the button finder in the positions which they assume when a button has been moved into the fork by the finder and showing the operating connections for the fork and the finder and certain other of the moving parts of the machine;

Fig. 6 is a view similar to Fig. 4, but showing the button finder withdrawn to expose the upper surface of the fork;

Fig. 7 illustrates the principal operating instrumentalities of the machine in the relative positions occupied by them at the time of the presentation of the work to the machine;

Fig. 8 is a view similar to Fig. 7, but showing the operating instrumentalities in the positions which they assume just prior to the beginning of a buttoning operation;

Fig. 9 shows the operating instrumentalities at the point in the cycle of operations of the machine when the main buttoning device has completed its endwise movement to dispose the material of the buttonhole fly at one side of a buttonhole in buttoned relation to a button;

Fig. 10 is a view in front elevation of the main buttoning device in the same position as in Fig. 9;

Fig. 11 is a view in plan of the work engaging portion of the main buttoning device in the position in which it is shown in Figs. 9 and 10;

Fig. 12 is a view of certain of the operating instrumentalities, the main buttoning device having been rotated somewhat from the position in which it is shown in Fig. 9; and

Fig. 13 illustrates the operating instrumentalities in the positions which they occupy at the time of the completion of the feeding of the button piece and the buttonhole fly.

The illustrative machine comprises a frame 2 from the front of which projects a fork 4 adapted to receive successively the buttons with respect to which buttoning operations are to be performed by the machine. During the operation of the machine, the buttons are successively supported on an anvil 6, and the marginal portion of the buttonhole fly in which the buttonholes are formed is guided by a bowed strip 8 supported at its ends from the sides of the machine frame. The strip 8 is cut away at 10 to receive the main buttoning device to be hereinafter described and a buttonhole finding finger 12 arranged to engage in a buttonhole of the fly and to move the fly inwardly to locate the buttonhole engaged by it in register with a button in the fork 4. As shown the finger 12 is pivoted at 14 to a bar 16 slidably mounted in the frame 2 of the machine and formed at its rear end with a laterally deflected portion 18 provided with a cam roll 20 riding in a cam groove 22 in a cam wheel 24 on the cam shaft 26. The portion 18 of the bar 16 is preferably forked to embrace the cam shaft 26 so as to guide the bar 16 in its movements. The finger 12 is normally projected downwardly through the recess 10 of the guide 8 by a spring 28 connected at one of its ends to a pin 30 on an upwardly extending portion of the finger 12 and at its other end by any suitable means to the bar 16. At its rear end, the finger 12 is provided with a pin 31 arranged to engage a cam surface 32 on a cam block 33 on rearward movement of the finger. The cam block 33

130

is slidably mounted in a recess in the machine frame 2 and is normally pressed forwards in the recess by a spring 34 to a point determined by a pin 36 on the frame engaging a shoulder on the cam block. The spring 34 is of less strength than the spring 28, in consequence of which, when the pin 31 in the rearward movement of the finger 12 is brought into engagement with the cam surface 32, the block 33 is moved rearwardly by the finger until the rear surface 37 of the block engages the inner wall 38 of the recess in which the block slides. Upon the engagement of the block 33 with the inner wall 38 of the recess, continued rearward movement of the finger 12 causes the roll 31 to ride down the cam surface 32, thus elevating the forward end of the finger 12 away from the buttonhole fly. When the continued movement of the finger 12 rearwardly brings the pin 31 into engagement with the under surface 40 of the cam block 33, the cam block is moved forwardly by the spring 34, with the result that upon the subsequent forward movement of the finger 12, the cam block maintains the finger above the fly until it attains substantially to the limit of its forward movement when the roll 31 rides upwardly on the cam surface 32 and permits the finger 12 again to engage the fly.

The buttonhole fly having been moved rearwardly by the buttonhole finder 12 to locate a buttonhole of the fly over a button in the fork 4, it is desirable that the fly be maintained in such position during the performance of the ensuing buttoning operation. In the illustrated construction, this is accomplished by a gripper lever 42 fulcrumed on the machine frame 2 and formed with a downwardly extending portion 44 arranged to grip the buttonhole fly adjacent to its edge against a block 46 stationarily mounted on the machine frame. The gripper 42 is normally maintained in inoperative relation to the block 46 by a spring 48 and is operated to grip the buttonhole fly against the block 46 by a bar 50 slidably mounted in the machine frame. The bar 50 is provided at its rear end with a roll 52 received in a slot 54 in a cam wheel 56 fast on the cam shaft 26. The rear end of the bar 50 is forked to embrace the cam shaft 26 in a manner analogous to the bar 16. In order to compensate for buttonhole flies of various thicknesses, the bar 50 is made in two pieces between which is interposed a spring 58 which yields more or less in accordance with the thickness of the buttonhole fly.

The buttoning devices comprise a main buttoning device 60 and the anvil 6 which constitutes a subsidiary buttoning device the buttoning device 60 and the anvil 6 being movable toward each other in a fixed path

substantially in line with a button in the fork 4. The buttoning device 60 is preferably formed from a rod or length of wire having a substantially straight body portion 62 and being bent adjacent to its end, first laterally of the body portion, as indicated at 64 (see Fig. 11), then away from the body portion both transverse to and in the direction of the line of extension of the body portion, as indicated at 66, and then backward toward the line of extension of the body portion to form a terminal portion 68 curved in a plane substantially at right angles to the line of extension of the body portion. The tip of the terminal curved portion 68 of the buttoning device 60 is preferably inclined backwardly and downwardly from its point, as indicated at 69, Fig. 10, to obviate any possibility of injury to the work by the device.

When the anvil 6 and the buttoning device 60 are moved toward each other, the terminal portion 68 of the buttoning device engages the material of the buttonhole fly at one side of a buttonhole in the fly and pushes it down into buttoned relation to a button in the fork 4. Meanwhile, the anvil 6 is raised into position to support the button during the completion of the buttoning operation which is effected by rotation of the device 60. After the buttoning operation is fully performed, the anvil 6 and buttoning device 60 are moved together laterally of the machine frame to feed the button piece and the buttonhole fly so as to present the next adjacent button on the button piece and next buttonhole of the buttonhole fly to the fork 4 and buttonhole finder 12 respectively, the recess 10 of the guide 8 being extended laterally of the machine to permit such movement of the buttoning device 60. To facilitate the feeding of the button piece and the buttonhole fly and the performance of the buttoning operation, the button holding fork 4 is withdrawn from the button during the buttoning operation. Preferably, also, the fork is so constructed as to permit the buttons to be tipped during the buttoning operations, thus causing them readily to enter the buttonholes. To this end the fork comprises two relatively movable arms 70 and 72, the former of which is withdrawn from the buttonhole during the buttoning operation at a point in advance of that at which the other arm 72 is withdrawn. The arm 70 is formed at the end of a bar 74 mounted to slide in the machine frame 2 and provided at its rear end, where it is forked to embrace the cam shaft 26, with a cam roll 76 riding in a cam groove 78 in a cam wheel 80 on the cam shaft 26. The other arm 72 of the button supporting fork 4 is formed as part of a bar 82 mounted to slide in the machine frame adjacent to the bar 74 and in substantial parallelism with it. At its rear end it

85

90

95

100

105

110

115

120

125

130

is forked to embrace the cam shaft 26 similarly to the bar 74 and is provided with a cam roll 84 received in a groove 86 in a cam wheel 88 on the shaft 26.

- 5 The anvil 6 is mounted in a carrier 90 at the front of the machine frame 2. As shown, the carrier is recessed at 92 to receive the anvil 6, and the anvil is formed with a downwardly extending shank 94 having a roll 96 at its lower end movable in a slot 98 in the carrier. The anvil 6 is normally thrust upwardly and outwardly from the carrier 90 to a point determined by engagement of the roll 96 with the upper wall of 10 the slot 98 by a spring 100 coiled about the shank 94. In order to enable the anvil 6 to co-operate with the buttoning device 60 in feeding the button piece and the buttonhole fly, the carrier 90 is mounted on a shaft 102 for sliding movement laterally of the frame of the machine. Vertical reciprocation of the anvil 6 is effected by raising and lowering the shaft 102 the ends of which are received in vertical slots 104 formed in uprights 106 on the machine frame. The shaft 102 is provided adjacent to its ends with arms 108 fixed to the shaft and pivoted at their outer ends to arms 110 fast on a shaft 112 mounted in fixed bearings in the 15 uprights 106. The hub of the arm 110 at the right of the machine, as seen in Fig. 1, is provided with downwardly extending arms 114 to which is fulcrumed a link 116 in turn connected at its rear end to a bell crank 20 lever 118 pivoted on a shaft 120 extending transversely of the machine frame. The other arm of the bell crank lever 118 is provided with a cam roll 122 which rides in a cam groove 124 in the cam wheel 56.
- 25 The buttoning device 60 is carried by a rod 126 to which it is secured in any suitable manner as by means of a set screw 128 or the like. The rod 126 is connected at its upper end to a sleeve 130 mounted to slide on a rod 132 carried by the forked end of an arm 134, the hub portion of which is loosely mounted on a shaft 138 extending transversely of the machine frame 2. Depending from the hub of the arm 134 is an arm 140 to which is connected a link 142 in turn pivoted to a bell crank lever 144 loosely mounted on a shaft 150 also disposed transversely of the frame of the machine. The rear arm 152 of the bell crank lever 144 is provided with a cam roll 154 riding in a cam groove 156 in the cam wheel 24. When the cam shaft 26 is operated, the rod 126 and the buttoning device 60 are reciprocated vertically by the connections above described.
- 30 The arm 70 of the button supporting fork 4 at that side of the buttonhole which is engaged by the buttoning device 60 in its downward movement is withdrawn just prior to the engagement of the buttoning device with the buttonhole fly, thus per-

mitting the device to dispose the material at that side of the buttonhole in buttoned relation to the button (see Fig. 11). The buttoning device 60 is then rotated to complete the buttoning operation, the arm 72 of the fork 4 being withdrawn just in advance of the tip of the terminal portion 68 of the device. The rod 126 which carries the buttoning device 60 passes through a carrier 158 slidably mounted on transverse shafts 160, and the rod is rotatably connected to the sleeve 130, for example, by means of a pin 162 on the rod lying in a groove in a boss 164 depending from the sleeve 130. Rotation of the rod 126 is effected by a barrel 166 rotatably mounted in the carrier 158 and keyed to the rod 126 in such a manner as to permit longitudinal movement of the rod relatively to the barrel but to cause the rod and the barrel to rotate together. The barrel 166 is rotated in the carrier 158 by pins 168 fitting into cam slots 169 in the barrel and carried by arms 170 depending from a yoke 172 having studs 173 mounted to slide in arms 174 fast on the shaft 138. The shaft 138 has depending therefrom an arm 176 to which is connected a link 178 the other end of which is in turn pivoted to an arm 180 of a bell crank lever mounted on the shaft 150 and having its other arm 182 provided with a cam roll 184 riding in a cam groove in the cam wheel 24.

35 After the completion of a buttoning operation, the button piece and buttonhole fly are fed by moving the anvil carrier 90 and the carrier 158 laterally of the machine on the shafts 102 and 160 respectively, the arrangement of the parts being such that the carriers 90 and 158 are actuated while the anvil 6 and the buttoning device 60 are still in engagement with the work following the completion of a buttoning operation. The buttoning device 60 in its downward movement presses the work against the anvil 6 forcing the anvil downwardly somewhat against the resistance of the spring 100, so that the anvil clamps the work yieldingly against the main buttoning device 60, such relation of the anvil 6 and the buttoning device 60 being maintained substantially constant during the movement of the parts to feed the work. In the illustrated construction, the carrier 158 has a member 188 extending upwardly therefrom on its rear side provided with a slot in which moves a pin 190 on an arm 192 fast to the end of a shaft 194 rotatable in bearings 196 and 198 on the machine frame. Fixed to the shaft 194 adjacent to the forward side of the bearing 198 is an arm 200 to the end of which is joined a link 202 connected at its other end to an arm 204 on a shaft 206 supported in bearings 208 and 210. Secured on the forward end of the shaft 206 is an arm 212 carrying a pin 214 movable in a slot 215

defined by blocks 216 and 218 on the carrier 90. On the rear end of the shaft 206 is an arm which has upstanding therefrom a rod 222 operated by an arm 223 on the shaft 120. 5 The shaft 120 is oscillated to raise and lower the arm 223 by a second arm 224 fixed to the shaft and having a cam roll 225 riding in a groove 226 in the cam wheel 56.

The spacing of the buttons and buttonholes, both on the same and different pieces of work, varies considerably. Accordingly, in order to enable the buttons to be presented to the fork 4 and the buttonholes to be properly aligned with the buttons in the fork, I provide mechanism for automatically varying the extent of feeding movement of the anvil carrier 90 and the carrier 158 in accordance with variations in the spacing of the buttons and buttonholes in the work 10 being operated upon. In the present exemplification of the invention this mechanism is controlled by the buttonholes of the buttonhole fly and comprises the buttonhole finding finger 12, the construction being such 15 that the work feeding movement of the anvil 6 and buttoning device 60 is suspended when the finger 12, which during the feeding of the work rides on the buttonhole fly, passes into a buttonhole. As shown, the rod 222 20 is arranged to be connected to the arm 223 by means of a latch 228 provided with a lip 230 disposed for engagement over the end of the arm. The lip 230 of the latch 228 is normally held in engagement with the arm 223 by a spring 231 connected at one end to an arm 232 of the latch and at its other end to a foot 234 depending from a block 236 on the rod 222. A pin 238 on the block 236 25 limits the movement of the latch 228 under the action of the spring 231. The upper end of the latch 228 is embraced by a bent pin 240 carried by an arm 242 fulcrumed on the bearing 198. A rod 244 slidably mounted in the frame 2 of the machine passes through 30 the arm 242 and is provided rearwardly of the arm 242 with a nut 246. The rod 244 is formed at its forward end with a depending portion having a slot 248 in which the pin 30 on the buttonhole finding finger 12 moves. With this construction, when the arm 223 is raised the anvil 6 and buttoning device 60 are moved to the left on the machine frame to feed the button piece and the buttonhole fly. Upon register of a buttonhole of the fly with the finger 12 and consequent downward movement of the finger into the buttonhole, the pin 30 carried by the finger, by engagement with the slot 248 of the rod 244, moves the rod 244 forwardly 35 and thereby, through the instrumentality of the arm 242, disengages the lip 230 of the latch 228 from the arm 223. Consequently, the work feeding movement of the anvil 6 and buttoning device 60 will be discontinued, the arm 223 completing its upward

movement without affecting the positions of such parts. When, in the continued operation of the machine, the arm 223 is again lowered, it engages the block 236 on the rod 222 and returns the anvil 6 and buttoning device 60 into alignment with the fork 4. In the meantime, however, the buttonhole fly engaging end of the finger 12 is raised so that when the arm 223 is depressed, the lip 230 of the latch 228 is permitted 70 again to engage over its end. 75

The feeding of the button piece and the buttonhole fly by the anvil 6 and buttoning device 60 causes the next adjacent button on the button piece to be aligned with the fork 4, the arms 70 and 72 of which are moved forwardly substantially simultaneously after the feeding movement of the button piece and buttonhole fly terminates. It may happen, however, for example, by 80 reason of the spacing of the buttons on the button piece varying somewhat from that of the buttonholes of the buttonhole fly, that a button will not be located so as properly to enter the fork when it is moved forward. 85 Accordingly, I provide a button finder operating to engage the buttons successively as the work is fed and to introduce them into the fork 4. As shown, the button finder comprises two hook members 250 pivoted at 90 252 to an enlargement 254 of a bar 256 slideable in the machine frame 2 above the bar 74. The bar 256 is preferably forked at its outer end to embrace the cam shaft 26 and is provided with a cam roll 258 riding in a 95 cam groove 260 in the cam wheel 80. The members 250 are normally pressed toward each other by springs 262 on the bar 256. They may be separated, however, in opposition to the springs 262 by a wedge 264 interposed between them and connected to a bar 266 arranged to slide over the bar 82. The bar 266 is preferably bifurcated at its rear end to embrace the cam shaft 26 and motion is imparted to it by means of a cam 100 roll 268 received in a cam groove 270 of the cam wheel 88. The wedge 264 maintains the members 250 separated when they are moved away from the button fork 4 to enable them to pass on opposite sides of the eye of a 105 button, after which the wedge is moved forwardly to permit the button engaging members to close on the eye of the button and to cause them to move the button into the button supporting fork 4 when they are 110 again moved toward the fork. After the members 250 have moved a button into the fork 4, they are separated by rearward movement of the wedge 264 and are then moved rearwardly to clear the upper surface 115 of the fork. 120

The manner of operation of the machine will now be described. The machine is stopped with the operating instrumentalities in the relative positions shown in Fig. 7. 130

The anvil 6 and the main buttoning device 60 are at the limits of their movement to the left (see Fig. 1) and are fully separated from each other. The buttonhole finding finger 12 is down in position to have a buttonhole of a buttonhole fly engaged over it. The gripper lever 42 is withdrawn from the gripper block 46, and the arms 70 and 72 of the button supporting fork 4 are projected forwardly to button receiving position.

In this position of the parts, the members 250, constituting the button finder, are withdrawn rearwardly of the button fork so as to clear the fork, as seen in Fig. 6. The work to be operated upon is presented to the machine with the first button to be buttoned introduced into the fork 4, and the corresponding buttonhole of the buttonhole fly engaged over the finger 12. When the machine is used to button shoes, they are passed through the space between the anvil carrier 90 and the machine frame. If a right shoe is to be buttoned, the button next to the throat 25 of the shoe is first introduced into the fork 4 with the button piece lying against the under surface of the fork. The buttonhole fly lies on the top of the anvil 6, and the marginal edge of the fly in which the buttonholes 30 are formed is turned back over the fork 4 with its upper surface engaging the bowed strip 8. When the machine is used to button a left shoe, the relation of the button piece and the buttonhole fly to the machine is the same as in the case of a right shoe except that the shoe is reversed, end to end, and the button adjacent to the upper end of the button piece is first introduced into the fork and the corresponding buttonhole of the buttonhole fly engaged over the end of the finger 12. Upon the starting up of the machine, the finger 12 is drawn back to locate the buttonhole engaged by it over the top of the button in the fork, after which the gripper lever 42 is swung to the left, as seen in Fig. 3, by the bar 50 to clamp the edge of the buttonhole fly against the block 46. Further movement of the buttonhole finding finger 12 causes it to be withdrawn from the buttonhole by reason of the engagement of the pin 31 on the finger with the cam surface 32 of the cam block 33. The finger 12 then continues back out of the way of the main buttoning device 60.

In the continued operation of the machine, the anvil carrier 90 and the carrier 158 are moved to the right to aline the anvil 6 and the buttoning device 60 with the button in the fork. The anvil 6 is moved up under the work, and the buttoning device 60 is moved downwardly toward the buttonhole fly, the parts being then in the positions exhibited in Fig. 8. Just prior to the engagement of the buttonhole fly by the buttoning device 60, the arm 70 of the fork 4 is with-

drawn from the button, thus permitting the buttoning device 60 to thrust the material of the buttonhole fly on the corresponding side of the buttonhole along the side of the button and to dispose it in buttoned relation to the button, as shown in Fig. 11. As the buttoning device 60 moves down, it tends to press the head of the button toward the arm 72 of the fork 4, so that during this part of the buttoning operation, the button is supported mainly by the arm 72, the buttoning instrumentalities being then in the positions shown in Fig. 9. The buttoning operation is completed by rotation of the buttoning device 60. After the buttoning device has been rotated to a point such that its tip over-hangs slightly the end of the arm 72 of the fork 4, as indicated in Fig. 12, the arm 72 of the fork is withdrawn from the button at a rate substantially equal to that of the advancing movement of the tip of the buttoning device, the relative positions of the end of the arm and the tip of the buttoning device remaining substantially unchanged as the arm 72 is withdrawn. Inasmuch as the arm 70 has been previously withdrawn from the opposite side of the button, the latter is permitted to tip during the rotation of the buttoning device, thus facilitating its entry into the buttonhole. The buttoning device 60 is preferably rotated to a point such as to cause its tip to engage the side of the buttonhole engaged by it in its endwise movement to insure that the material about the buttonhole will be fully disposed in buttoned relation to the button.

It will be apparent from the foregoing that the buttoning device 60 first disposes the material of the fly adjacent to one side of a buttonhole in buttoned relation to a button and then by its rotation presses the material at the other side of the buttonhole downwardly along the head of the button, simultaneously clearing the side of the button adjacent to the first-mentioned side of the buttonhole and tipping the button over the material of the fly at such side of the buttonhole. The terminal portion 68 of the buttoning device 60 (see Fig. 11) converges from its tip toward the axis of rotation of the device. Consequently, when the buttoning device is rotated from the position indicated in Fig. 11 to complete a buttoning operation, the spiral portion 68 of the device tends by a camming action, as well as by forcing the material of the fly downwardly along the button head, to tip the button into the buttonhole and also to draw the material at the side of the buttonhole inwardly beneath the head of the button. The construction and manner of operation of the buttoning device 60 are such as manifestly to adapt it to operate efficiently on buttons, the heads of which vary within wide limits in size and contour. For example, inasmuch as the

buttoning device engages the work only at points adjacent to or about the periphery of the button, its action will not be affected by variations in the shape of the central portion of the crown of the button.

After a buttoning operation is completed, the bar 50 is moved rearwardly, thus permitting the spring 48 to withdraw the gripper lever 42 from clamping engagement with the buttonhole fly, the button piece and buttonhole fly being yieldingly held against the buttoning device 60 by the anvil 6. The anvil 6 and buttoning device 60 are then moved to the left (Fig. 1), carrying the button piece and buttonhole fly with them. As the anvil 6 and the buttoning device 60 are moved to feed the work, the buttonhole finding finger 12 is moved forwards, its end engaging and riding upon the upper surface of the fly as the work is fed. Upon engagement of the finger 12 in a buttonhole of the fly, the end of the finger is depressed under the action of the spring 28, thereby disconnecting the latch 228 from the arm 223 and suspending the feed of the work. The anvil 6 and buttoning device 60, after having completed their feeding movements, are separated to starting positions. At the same time in the cycle of operations of the machine, the button finder, comprising the button engaging members 250, is moved forward and closes around the eye of the next adjacent button on the button piece and draws it into the fork 4 which is moved forwardly at substantially the same time, the members 250 continuing their rearward movement after the introduction of the button in the fork to clear the upper surface of the fork. This completes a cycle of operations of the machine, and the machine will repeat until the operator's foot is lifted from the controlling treadle (not shown).

Having thus described my invention, what I claim as new and desire to secure by Letters Patent of the United States is:

1. In a buttoning machine, means for disposing the material adjacent to a buttonhole of a buttonhole fly in buttoned relation to a button on a button piece, a support for the button, and means for moving said means and the support together with the work engaging portions of said means and the support in substantially constant relation to each other to feed the buttonhole fly and the button piece.

2. In a buttoning machine, devices operable successively on the buttons on a button piece and on the material adjacent to the buttonholes of a buttonhole fly to perform buttoning operations, and means for moving said devices while still in engagement with the button piece and the fly following the completion of a buttoning operation to feed the button piece and the fly.

3. In a buttoning machine, devices opera-

ble on a buttonhole fly and the buttons on a button piece, means for effecting relative movement of said devices to perform a buttoning operation on a button on the button piece with respect to a buttonhole of the 70 fly, and means for imparting movement of another character to said devices to feed the button piece and the buttonhole fly.

4. In a buttoning machine, mechanism for performing buttoning operations successively 75 on the buttons of a button piece with respect to the buttonholes of a buttonhole fly, comprising devices for effecting relative movement of the buttons and the material adjacent to the buttonholes of the buttonhole fly 80 to cause the buttons to enter the buttonholes and means for moving said devices together after the completion of each buttoning operation to cause them to feed the button piece and the buttonhole fly by engagement 85 with the button piece and the buttonhole fly substantially in the manner in which the buttoning operation is completed.

5. In a buttoning machine, a button support movable laterally on the frame of the 90 machine in the direction of the length of a line of buttons on the button piece of a shoe and means co-operating with the support to perform buttoning operations successively 95 on the buttons of the button piece with respect to the buttonholes of a buttonhole fly.

6. In a buttoning machine, a button support, yielding means tending to move said support in one direction, and means for pressing the material adjacent to a buttonhole of a buttonhole fly against the support in the opposite direction against the tendency of the yielding means to dispose the material in buttoned relation to a button on the support. 100

7. In a buttoning machine, mechanism for performing buttoning operations successively on the buttons on a button piece with respect to the buttonholes of a buttonhole fly, comprising a button support movable 110 laterally on the frame of the machine, and means co-operating with the support to feed the button piece and the buttonhole fly.

8. In a buttoning machine, a work support movable laterally on the frame of the machine, a member movable with the work support to feed a button piece and a buttonhole fly, and means for moving the member towards the support to perform a buttoning operation on the buttons of the button piece 115 with respect to the buttonholes of the buttonhole fly.

9. In a buttoning machine, mechanism for performing buttoning operations successively on the buttons on a button piece with respect to the buttonholes of a buttonhole fly, comprising a button support, means for reciprocating the support vertically, and means for advancing the button piece and buttonhole fly intermittently relatively to 125

- the support to locate the buttons on the button piece and the buttonholes of the fly successively in the vertical plane of the support.
- 5 10. In a buttoning machine, mechanism for performing buttoning operations successively on the buttons of a button piece with respect to the buttonholes of a button-hole fly, comprising a button support, a 10 member operable on the buttonhole fly to dispose the material adjacent to a button-hole of the fly in buttoned relation to a button on the support, and means for moving the support and member together to feed 15 the button piece and the buttonhole fly.
11. In a buttoning machine, a button holder constructed to receive a single button at a time, devices operable on a button in the holder and on a buttonhole fly to perform 20 a buttoning operation on the button with respect to a buttonhole of the fly, and means for moving the devices relatively to the holder to feed the work.
12. In a buttoning machine, mechanism for performing buttoning operations successively on the buttons on a button piece with respect to the buttonholes of a buttonhole fly, comprising a button holder constructed to receive a single button at a time and 30 means for taking each button from the holder and feeding it beyond the holder to present the following buttons on the button piece to the holder successively.
13. In a buttoning machine, mechanism for performing buttoning operations successively on the buttons on a button piece with respect to the buttonholes of a button-hole fly, comprising a slidable button supporting fork, means for sliding the fork 40 away from a button in the fork after the work has been engaged by the buttoning mechanism, and means for feeding the button piece and buttonhole fly after the fork has been withdrawn.
- 45 14. In a buttoning machine, a button holder constructed to receive a single button at a time and mechanism cooperating with the holder to perform buttoning operations successively on the buttons on a button piece 50 with respect to the buttonholes of a button-hole fly, said mechanism being constructed and arranged to feed the button piece and buttonhole fly past the holder and comprising a buttoning device movable toward a 55 button in the holder.
15. In a buttoning machine, a button holder, devices operable on a button in the holder and on a buttonhole fly to perform a buttoning operation on the button with respect to a buttonhole of the fly, said devices 60 being constructed and arranged to clamp the work between them, means for moving the button holder away from the button after the work has been engaged by the buttoning devices, and means for moving the 65
- devices relatively to the button holder to feed the work.
16. In a buttoning machine, a button holder, an anvil, a buttoning device, means for moving the anvil and buttoning device toward each other in line with a button in the holder to perform a buttoning operation on the button with respect to a buttonhole of a buttonhole fly, and means for moving the anvil and the buttoning device together away from the holder to feed the button piece and the buttonhole fly. 70
17. In a buttoning machine, a button holder, devices movable toward each other in line with a button in the holder to perform a buttoning operation on the button with respect to a buttonhole of a buttonhole fly and movable away from each other to release the button and the buttonhole fly, and means for moving the devices together toward and away from the button holder, said means being constructed to move the devices away from the button holder while they are in engagement with the work so as 75 to feed the work.
18. In a buttoning machine, devices operable upon a button and a buttonhole fly, and operating means for said devices operable to move them toward each other to perform a buttoning operation on the button with respect to a buttonhole of the buttonhole fly and to move them away from each other to release the button and the buttonhole fly, said operating means being constructed and arranged to move the devices together in opposite directions intermediate between the first-mentioned movements so as to feed the work and restore the devices to button engaging position. 80
19. In a buttoning machine, a button receiving member having a movable arm, devices operable on a button in the member and on the buttonhole fly to perform a buttoning operation, and means for moving the arm to facilitate the buttoning operation. 85
20. In a buttoning machine, a button holder having a movable member, a support for a button piece and a buttonhole fly, a buttoning device movable towards the support, and means for simultaneously moving the buttoning device and the member to perform a buttoning operation on a button with respect to the buttonhole of a buttonhole fly. 90
21. In a buttoning machine, a button supporting fork, comprising relatively movable arms, an anvil, a device movable toward the anvil to perform a buttoning operation on a button in the fork with respect to a button-hole of a buttonhole fly, and means for moving one arm of the fork relatively to the other to enable the button to be tipped, thereby to facilitate its entrance into the buttonhole. 95
22. In a buttoning machine, a button sup- 100
- 105
- 110
- 115
- 120
- 125
- 130

- porting fork comprising relatively movable arms, devices operable on a buttonhole fly and on a button in the fork to perform a buttoning operation on the button with respect to a buttonhole of the buttonhole fly, and means for moving one arm of the fork relatively to the other to enable the button to be tipped to facilitate the operation of the buttoning devices.
- 5 23. In a buttoning machine, a button supporting fork comprising relatively movable arms, devices movable toward each other in line with a button in the fork to perform a buttoning operation on the button with respect to a buttonhole of a buttonhole fly, and means for moving the arms of the fork successively away from the button, and means for moving the devices to feed the work.
- 10 24. In a buttoning machine, a movable button holder, means for gripping a button-hole fly, devices operable on the button hole fly and on the button in the holder to perform a buttoning operation on the button with respect to a buttonhole of the button-hole fly while the fly is engaged by the gripping means, means for moving the button holder to release the button, means for releasing the gripping means from the fly, and means for operating the devices to feed the work after the fly and button have been released.
- 15 25. In a buttoning machine, a holder for successively receiving the buttons on the button piece of a shoe, a finder for successively engaging in the buttonholes of a buttonhole fly, means for moving the finder to locate the buttonholes over the corresponding buttons, and devices for performing buttoning operations on the buttons and buttonholes.
- 20 26. In a buttoning machine, devices operable on a buttonhole fly and on the buttons of a button piece to perform buttoning operations successively on the buttons of the button piece with respect to the buttonholes of the buttonhole fly, means for operating the devices to feed the button piece and the buttonhole fly, and a finder arranged for successive engagement with the buttonholes of the fly as it is fed and operable to move the fly to dispose the buttonholes of the fly in position to enable the buttoning operations to be performed.
- 25 27. In a buttoning machine, a button holder, mechanism co-operating with the holder to perform buttoning operations successively on the buttons on a button piece with respect to the buttonholes of a button-hole fly, said mechanism comprising means for feeding the button piece and buttonhole fly relatively to the holder, and a finder arranged for successive engagement with the buttonholes of the fly as it is fed and operable to move the fly to position the buttonholes of the fly successively in line with the buttons in the holder.
- 30 28. In a buttoning machine, a button holder, devices operable on a button in the holder and on a buttonhole fly to perform a buttoning operation on the button with respect to a buttonhole of the buttonhole fly, means for withdrawing the button holder from the button after work has been engaged by said devices, means for operating said devices to feed the work, and a finder arranged for successive engagement with the buttonholes of the fly as it is fed and operable to move the fly to position the buttonholes of the fly successively over the buttons in the holder so as to enable the buttoning devices to dispose the material adjacent to the buttonholes in buttoned relation to the buttons.
- 35 29. In a buttoning machine, a button holder, devices operable on a button on a button piece, when disposed in the holder, and on a buttonhole fly to perform a buttoning operation on the button with respect to a buttonhole of the buttonhole fly, means for withdrawing the button holder from the button after the work has been engaged by said devices, means for operating said devices to feed the work, a button finder for engaging the next adjacent button on the button piece and moving it into the holder, and a finder arranged for engagement with the next adjacent buttonhole of the fly and operable to move the fly to position the buttonhole over the button so as to enable the buttoning devices to dispose the material adjacent to the buttonhole in buttoned relation to the button.
- 40 30. In a buttoning machine, a button holder, a button finder for moving a button into the holder, a buttonhole finder for moving a buttonhole fly to dispose a buttonhole of the fly over the button in the holder, means for gripping the buttonhole fly, and devices for performing a buttoning operation on the button with respect to a button-hole of the buttonhole fly while the fly is held by the gripping means.
- 45 31. In a buttoning machine, a button holder, a button finder for moving a button into the holder, a buttonhole finder for moving a buttonhole fly to dispose a buttonhole of the fly over the button in the holder, means for gripping the buttonhole fly, devices for performing a buttoning operation on the button with respect to the buttonhole while the fly is held by the gripping means, means for releasing the work from constraint by the gripping means, and means for operating said devices to feed the work after the fly has been released by the gripping means so as to bring the adjacent button of the button piece and buttonhole of the fly into position for engagement respectively by the button finder and buttonhole finder.
- 50 32. In a machine for performing buttoning operations successively on a buttonhole

- fly, and the buttons on a button piece, means for feeding the work and means separate from the feeding means and controlled by the work for governing the extent of movement of the feeding means.
33. In a machine for operating on the uppers of boots and shoes, means for feeding a portion of the upper, and means separate from the feeding means and controlled by the work for governing the extent of movement of the feeding means.
34. In a buttoning machine, means for feeding the buttons on a button piece and a buttonhole fly, and a buttonhole finder constructed and arranged to stop the feed when the finder engages a buttonhole.
35. In a buttoning machine, a spring pressed finder, means for feeding a buttonhole fly past the finder, and means controlled by the entry of the finder into a buttonhole for stopping the feeding means.
36. In a machine for operating on the uppers of boots and shoes, means for feeding a buttonhole fly, a buttonhole finder, and means controlled by the finder for governing the operation of the feeding means.
37. In a machine for operating on the uppers of boots and shoes, means for feeding the work, a buttonhole finder adapted to ride on the buttonhole fly as it is fed, and means operating upon engagement of the finder in a buttonhole of the fly to arrest the operation of the feeding means.
38. In a buttoning machine, devices operable on a button on a button piece to perform a buttoning operation on the button with respect to a buttonhole of a buttonhole fly, means for operating said devices to feed the work, a buttonhole finder arranged to ride on the fly, and means operated by the finder to arrest the operation of the operating means.
39. In a machine for operating on the uppers of boots and shoes, means for feeding a buttonhole fly, operating means for the feeding means comprising connections adapted to be made and broken, and means controlled by the work for breaking said connections, thereby to suspend the operation of the feeding means.
40. In a buttoning machine, devices operable on a buttonhole fly and a button on a button piece to perform a buttoning operation on the button with respect to a buttonhole of the fly, means for operating the devices to feed the work, comprising connections adapted to be made and broken, a buttonhole finder, and means operable upon engagement of the finder with a buttonhole to break the connections, thereby to suspend the operation of the operating means.
41. In a buttoning machine, buttoning devices, means for moving one of the devices toward another of the devices in a fixed path to dispose the material adjacent to a buttonhole of a buttonhole fly in buttoned relation to a button on a button piece, means for moving the devices to feed the button piece and buttonhole fly, and means for suspending the feeding movement of the devices when the next adjacent buttonhole of the fly has been brought substantially into the path of movement of the first-mentioned device toward the other device.
42. In a buttoning machine, a button support, a buttoning device movable toward the support in a fixed path to dispose the material adjacent to a button hole of a buttonhole fly in buttoned relation to a button on the support, means for moving the support and buttoning device to feed the work, and means for suspending the feeding movement of the support and the device when the next adjacent buttonhole of the buttonhole fly has been brought substantially into the path of movement of the device toward the support.
43. In a buttoning machine, a buttonhole finder movable to locate the buttonholes of a buttonhole fly with respect to the corresponding buttons of a button piece, and means for feeding the buttonhole fly and the button piece transversely with respect to the finder.
44. In a buttoning machine, a buttonhole finder operable to move a buttonhole fly to locate the buttonholes successively in position to receive the buttons on a button piece, means for imparting to the finder reciprocal and pivotal movements to engage and move the buttonholes successively into position, and means for feeding the buttonhole fly with respect to the finder.
45. In a buttoning machine, a reciprocating buttonhole finder operable to move a buttonhole fly to locate a buttonhole of the fly in position to receive a button on a button piece, and means for withdrawing the finder from a buttonhole of the fly constructed to space the finder from the buttonhole fly upon reverse movement of the finder.
46. In a buttoning machine, a reciprocating buttonhole finder, a cam block for withdrawing the finder from a buttonhole of a buttonhole fly when the finder moves in one direction, and means for moving the cam block to retain the finder in spaced relation to the fly during reverse movement of the finder.
47. In a buttoning machine, a pivoted buttonhole finder operable, when moved in one direction, to locate a buttonhole of a buttonhole fly over a button on a button piece, means for reciprocating the finder, a movable cam block for withdrawing the finder from the buttonhole, a spring for moving the cam block to maintain the finder in spaced relation to the buttonhole fly, and means for limiting the movement of the cam block to permit the finder again to engage

the buttonhole fly as the finder moves in the other direction.

48. In a machine for operating on the uppers of boots and shoes, a member provided with a recess and having a surface disposed for engagement with the outer surface of a buttonhole fly, a finger arranged to project through the recess into engagement with a buttonhole of the fly, means for reciprocating the finger in the recess to locate the buttonhole in position to receive a button, and controlling means for the finger constructed to withdraw the finger from the buttonhole fly at one point of the recess and to cause the finger to pass through the recess into engagement with the buttonhole fly at another point of the recess.

49. In a machine for performing buttoning operations successively on a buttonhole fly and the buttons on a button piece, means for feeding the button piece, a button holder, a button finder, and means for operating the button finder intermediate between the feeding movements of the button piece to move the buttons on the button piece successively into the holder.

50. In a buttoning machine, a button holding fork, and a button finder for locating a button of a button piece at the opening of the fork and moving it into the fork.

51. In a buttoning machine, a button holder and a pair of hook members operable to engage around the eye of a button and to move it into the holder.

52. In a buttoning machine, a button holder, a pair of button engaging devices for moving a button into the button holder, means tending normally to move the devices towards each other, and means for separating the devices to enable them to pass on opposite sides of the eye of a button, said separating means being operable to permit the devices to close on the eye of the button.

53. In a buttoning machine, a button holder, a pair of button engaging members, means for moving the button engaging members toward and from the button holder, means tending normally to press the engaging members together, a wedge for controlling the engaging members, and operating means for the wedge constructed to move the wedge relatively to the members to separate said members upon movement of said members away from the button holder, thus enabling the members to pass on opposite sides of the eye of a button, and to move the wedge in a reverse direction relatively to said members previous to the next succeeding movement of the members towards the button holder so as to cause said members to close on the eye of the button and to move the button into the button holder upon movement of said members toward the button holder.

54. In a buttoning machine, buttoning

mechanism constructed to dispose the material of a buttonhole fly adjacent to one side of a buttonhole of the fly in buttoned relation to a button and then to press the material of the fly at the other side of the buttonhole into buttoned relation to the button, said mechanism being constructed and arranged to clear the side of the button adjacent to the first-mentioned side of the buttonhole previous to the completion of a buttoning operation and to tip the button over the material of the fly at the first-mentioned side of the buttonhole while the material at the last-mentioned side of the buttonhole is being pressed into buttoned relation to the button.

55. In a buttoning machine, buttoning mechanism constructed to dispose the material of a buttonhole fly adjacent to one side of a buttonhole of the fly in buttoned relation to a button and then to press the material of the fly at the other side of the button into buttoned relation to the button, said mechanism being constructed and arranged to clear the side of the button adjacent to the first-mentioned side of the buttonhole previous to the completion of a buttoning operation and to tip the button over the material of the fly at the first-mentioned side of the buttonhole while the material at the last-mentioned side of the buttonhole is being pressed into buttoned relation to the button, a button holder, and means for withdrawing the holder from the button to enable the buttoning mechanism to operate in the manner described.

56. In a buttoning machine, buttoning mechanism constructed to dispose the material of a buttonhole fly adjacent to one side of a buttonhole of the fly in buttoned relation to a button and then to press the material of the fly at the other side of the button into buttoned relation to the button, said mechanism being constructed and arranged to clear the side of the button adjacent to the first-mentioned side of the buttonhole previous to the completion of a buttoning operation and to tip the button over the material of the fly at the first-mentioned side of the buttonhole while the material at the last-mentioned side of the buttonhole is being pressed into buttoned relation to the button, a button holder comprising relatively movable parts, means for withdrawing one of said parts from beneath the side of the button adjacent to the first-mentioned side of the buttonhole of the fly to enable the material of the fly to be disposed in buttoned relation to the button while it is supported by another part of the holder and to permit the button to be tipped during the completion of the buttoning operation, and means for withdrawing said other part of the holder from the button after the material at the first-mentioned side of the button has been disposed in buttoned

130

relation to the button to enable the material of the fly at the other side of the buttonhole to be pressed into buttoned relation to the button.

57. In a buttoning machine, a buttoning device operable to dispose the material of a buttonhole fly adjacent to one side of a buttonhole in the fly in buttoned relation to a button and constructed upon rotation to clear the adjacent side of the button and to press the material of the buttonhole fly at the other side of the button into buttoned relation to the button, while simultaneously tipping the button over the material at the first-mentioned side of the buttonhole, and means for rotating the buttoning device.

58. In a buttoning machine, means for locating a buttonhole fly with a buttonhole of the fly in position to receive a button, and a device mounted for rotary movement around the button for disposing the material of the fly adjacent to the buttonhole in buttoned relation to the button.

59. In a buttoning machine, a buttoning device, means for imparting a movement of translation to said device to dispose the material adjacent to a buttonhole of a buttonhole fly at one point about the buttonhole in buttoned relation to a button, and means for rotating said device to complete the buttoning operation with respect to the button.

60. In a buttoning machine, a support for a button and a buttonhole fly, and a buttoning device constructed and arranged to rotate about the axis of the button to dispose the material of the fly in buttoned relation to the button.

61. In a buttoning machine, means for supporting a button and a buttonhole fly, and a buttoning device mounted to rotate on an axis intersecting the button, said device having a terminal portion diverging from said axis to act as a cam on the material around a buttonhole to press it into buttoned relation to the button.

62. In a buttoning machine, means for supporting a button and a buttonhole fly, a buttoning device having a portion to engage the material of the buttonhole fly, and means for rotating said buttoning device to cause its fly engaging portion to act progressively around a buttonhole to force the material of the fly into buttoned relation to the button.

63. In a buttoning machine, means for supporting a button and a buttonhole fly, and a rotary buttoning device having a spiral portion to wedge the material of the buttonhole fly progressively under the head of a button.

64. In a buttoning machine, a substantially cork-screw shaped buttoning device, means for imparting to the device a movement of translation to dispose the material at one point about a buttonhole of a button-

hole fly in buttoned relation to a button, and means for rotating the buttoning device to complete the buttoning operation with respect to the button.

65. In a buttoning machine, a buttoning device comprising a strip of material having a substantially straight body portion and a terminal portion curved in a plane substantially at right angles to the line of extension of the body portion.

66. In a buttoning machine, a rotary buttoning device having a terminal work-engaging portion curved in a plane transverse to the axis of rotation of the device and converging from its tip toward the axis of rotation of the device.

67. In a buttoning machine, a rotary buttoning device comprising a work-engaging portion movable around a button substantially in the plane of the under surface of the button.

68. In a buttoning machine, buttoning mechanism operable to dispose the material of a buttonhole fly adjacent to one side of a buttonhole of the fly into buttoned relation to a button, and comprising a member movable around the button substantially in the plane of the under surface of the button to complete the buttoning operation.

69. In a buttoning machine, a buttoning device formed from a strip of wire having a substantially straight body portion, said strip being bent adjacent to its end first laterally of the body portion, then away from the body portion in the direction of extension of the body portion, and then backwardly toward the line of extension of the body portion and terminating in a curved portion disposed in a plane transverse to its body portion.

70. In a buttoning machine, a buttoning device, means for moving the device endwise, a sliding frame through which the device passes, means for reciprocating the frame to effect lateral movement of the device, and means carried by the sliding frame for rotating the device.

71. In a buttoning machine, buttoning mechanism comprising a device consisting of a strip of material having a substantially straight body portion and a terminal portion offset laterally from the body portion and curved in a plane substantially at right angles to the line of extension of the body portion and means for moving the buttoning device endwise into engagement with the material adjacent to a buttonhole of a buttonhole fly, means for locating the buttonhole fly in such relation to the buttoning device that the tip of the terminal curved portion of the device will engage the buttonhole fly at one side of the buttonhole of the fly and the part of the terminal curved portion remote from the tip will engage the fly at the opposite side of the buttonhole, and

means for operating the buttoning mechanism to complete the performance of the buttoning operation.

72. In a buttoning machine, a button holder comprising two relatively movable parts, means for locating a buttonhole fly with a buttonhole of the fly in register with a button in the holder and with one of the parts of the button holder underlying the buttonhole fly on one side of the buttonhole, a buttoning device movable into engagement with the buttonhole fly at the side of the buttonhole overlying said part, means for withdrawing said part of the button holder from beneath the side of the buttonhole, means for moving the buttoning device into engagement with the buttonhole fly to dispose the material at the side of the buttonhole in buttoned relation to the button, and means for imparting movement of another character to the buttoning device to complete the buttoning operation.

73. In a buttoning machine, a button holding fork comprising two relatively movable arms, means for locating a buttonhole fly with a buttonhole of the fly in register with a button in the fork and with one of the arms of the button holder underlying the buttonhole fly on one side of the buttonhole and the other of the arms of the button holder underlying the buttonhole fly on the other side of the buttonhole, a buttoning device movable by translation into engagement with the buttonhole fly at the side of the buttonhole overlying the first-mentioned arm, means for withdrawing said arm from beneath the side of the buttonhole, means for imparting a movement of translation to the buttoning device to dispose the material of the buttonhole fly at that side of the buttonhole in buttoned relation to the button, means for rotating the buttoning device to dispose the material of the buttonhole fly at the other side of the buttonhole in buttoned relation to the button, and means for withdrawing the other arm of the button holder from the side of the buttonhole in advance of the rotary movement of the device.

74. In a buttoning machine, a button holding fork comprising two relatively movable arms, means for locating a buttonhole fly with a buttonhole of the fly in register with a button in the fork and with one of the arms of the button holder underlying the buttonhole fly on one side of the buttonhole and the other of the arms of the button holder underlying the buttonhole fly on the other side of the buttonhole, a buttoning device movable into engagement with the buttonhole fly at the side of the buttonhole overlying the first-mentioned arm and comprising a fly engaging portion adapted to lie substantially flat on the fly, means for withdrawing said arm of the button holding fork from beneath the side of the buttonhole before the fly is engaged by the buttoning device, means for moving the buttoning device so as to bring the fly engaging portion of the device below the level of the upper surfaces of the arms of the button holder to dispose the material at that side of the buttonhole fly in buttoned relation to the button, means for withdrawing the other arm of the button holder from beneath the other side of the buttonhole fly, and means for rotating the buttoning device to cause the fly engaging portion of the device to follow the last-mentioned arm in its withdrawing movement, thus completing the buttoning operation.

75. In a machine for performing successive buttoning operations on shoes, an operating tool and a cooperating work support constructed and arranged to have relative movement of approach to effect a buttoning operation on the buttons of the button piece with respect to the buttonholes of the buttonhole fly, means for moving both the operating tool and the work support in another direction to feed the work, and means for gripping the work in the new position while the operating tool and the work support separate and return to their original positions.

In testimony whereof I have signed my name to this specification.

HERBERT E. ENSLIN.
